UNITED STATES PATENT OFFICE

139,744

DESIGN FOR A TOY AIRPLANE

David H. Faber, Rockville Centre, N. Y.

Application September 22, 1944, Serial No. 115,399

Term of patent 3½ years

(Cl. D34—15)

To all whom it may concern:

Be it known that I, David H. Faber, a citizen of the United States, residing in Rockville Centre, county of Nassau, and State of New York, have invented a new, original, and ornamental Design for Toy Airplane, of which the following is a specification, reference being had to the accompanying drawing, forming part thereof.

Fig. 1 is a perspective view of a toy airplane showing my new design; and

Fig. 2 is a top plan view thereof.

I claim:

The ornamental design for a toy airplane, as shown.

DAVID H. TABER.

Design No. 139,744.

CERTIFICATE OF CORRECTION.

December 19, 1944.

DAVID H. FABER.

It is hereby certified that error appears in the above numbered patent requiring correction as follows: In the signature to the printed specification, for "DAVID H. TABER" read --DAVID H. FABER--; and that the said Letters Patent should be read with this correction therein that the same may conform to the record of the case in the Patent Office.

Signed and sealed this 27th day of February, A. D. 1945.

(Seal)

Leslie Frazer
Acting Commissioner of Patents.
